UNITED STATES PATENT OFFICE

2,266,766

DEVICE FOR FREEZING LIQUIDS

James S. Knight, Chicago, Ill.

Application February 6, 1933, Serial No. 655,383
Renewed September 28, 1939

3 Claims. (Cl. 62—114)

This invention relates to a device for freezing liquids, such as ice cream, and has for its object to provide a new and improved device of this description. The invention has as a further object to provide a device of the kind described with a freezing coil around the outside of the inner wall and having a solid metal contact with said wall. The invention has as a further object to provide a vertical freezer of this description. The invention has a further object to provide a freezer which shall be compact, cheap in construction and efficient in operation. The invention has other objects which are more particularly pointed out in the accompanying description.

Referring now to the drawings, Fig. 1 is a vertical sectional view through one form of freezer embodying the invention;

Fig. 2 is an enlarged sectional view of the upper end of the device;

Fig. 3 is a sectional view taken on line 3—3 of Fig. 2;

Fig. 4 is a sectional view taken on line 4—4 of Fig. 2;

Fig. 5 is a view of the clamping member separate from the shaft;

Fig. 6 is a view similar to Fig. 2 showing the parts in their unclamped position;

Fig. 7 is an enlarged sectional fragmentary view showing the contact of the coil with the receptacle;

Fig. 8 is an enlarged sectional view taken on line 8—8 of Fig. 1.

Fig. 9 is a fragmentary section showing a modified construction.

Like numerals refer to like parts throughout the several figures.

Referring now to the drawings, I have shown a receptacle 1 which receives the material to be frozen. This receptacle is made of good conducting material, such as metal. Surrounding the receptacle 1 is a coil 2 through which the refrigerant is circulated. This coil is preferably arranged so as to have an intimate or metal contact with the receptacle 1. I prefer to have the coil tightly wound around the receptacle 1, and I may then solder the coil to the receptacle 1 so as to make a metallic connection. This solder is shown at 3. The coil is preferably coiled about the receptacle 1, a coil at a time, and soldered as it is coiled so that when the complete coil is formed it will be completely soldered to the receptacle 1. I may arrange the coil so that the inlet 4 is at the bottom of the coil, the refrigerant coming in at the bottom and circulating around the receptacle 1 through the coil and being dis-

charged at the top thereof into the discharge pipe 5. The pipe 5 may be used as the inlet if desired, or the inlet may be arranged at any position of the coil if desired. There is an outer casing 6 on the outside of the coil 2 and suitable heat insulating material 7 is provided for insulating the coil 2 and the receptacle 1.

Suitable means are provided in the receptacle 1 for agitating the material as it is being frozen. 10 This agitating means is driven in any desired manner, as for example by a motor 8 which is located vertically below the receptacle 1. This motor has its shaft connected to the usual gear head 9 so as to secure the desired driving speed.

The shaft 10 driven by the motor is coupled to the shaft 11 which drives the agitating device, by a coupling which consists of a metal member 12 connected with the shaft 10 and a metal member 13 connected with the shaft 11, there being a connecting element 14 between them which is made of non-metallic material such as leather. The members 12 and 13 are preferably provided with three arms 15 which do not register. The arms of the member 12 are connected to the non-metallic member 14 by suitable connecting devices 16, and the arms of the member 13 are connected to the non-metallic member 14 at different points by the connecting devices 17. It will thus be seen that there is provided an elastic connection between the motor shaft and the agitating device in the receptacle 1. The shaft 11 projects into the receptacle 1 and is connected with a rotatable frame so as to rotate it. This frame consists of the bottom member 18 and the top member 22 connected together by the connecting member 18a. Extending between the members 18 and 22 are the shafts 19 and 20 rotatably mounted in said members. There are also scrapers 21 rotatably mounted upon the members 18 and 22.

Connected with the shaft 19 is a gear 23, and connected with the shaft 20 is a gear 24. These gears are connected together by a gear 25. The gear 25 is connected with a shaft 26, being keyed thereon. The shaft 26 has a non-circular end 27 which fits into a noncircular opening in the end of the member 28. The member 28 has a flange 29 which engages a shoulder 30 on the cover 31. The member 28 has a projecting part 32 smaller in diameter than the body portion thereof which projects through a spring collar 33. This spring collar has the spring arms 34. A handle 36 is provided with a hollow screw threaded hub 37 55 which surrounds the part 32 and the spring col-

Connected with the shaft 19 is a gear 23, and connected with the shaft 20 is a gear 24. These gears are connected together by a gear 25. The gear 25 is connected with a shaft 26, being keyed thereon. The shaft 26 has a non-circular end 27 which fits into a noncircular opening in the end of the member 28. The member 28 has a flange 29 which engages a shoulder 30 on the cover 31. The member 28 has a projecting part 32 smaller in diameter than the body portion thereof which projects through a spring collar 33. This spring collar has the spring arms 34. A handle 36 is provided with a hollow screw threaded hub 37 which surrounds the part 32 and the spring col-

lar 33 and which engages a screw thread in the hollow upper end 38 of the cover 31.

When the handle 36 is unscrewed or loosened the shaft 26 and its attached gear 25 is free to rotate, and hence when the shaft 11 is rotated the shafts 19 and 20 are not rotated, the gear 25 running around with the gears 24 so that said latter gears are not rotated, but the beater arms 20a on said shafts move through the material in the receptacle but without rotating.

When the handle 36 is screwed down or tightened this causes the spring arms 34 of the spring collar 33, due to the inclined faces 39, to be compressed so as to frictionally engage the part 32 and the hub 37 of the handle 36 and stop the rotation of the shaft 26. This holds the gear 25 stationary. The rotation of the shaft 11 now causes the gears 24 to rotate as they rotate around the stationary gear 25, and causes the shafts 19 and 20 to rotate, causing the beater arms to rotate about the axis of the shafts 19 and 20 and to also move about through the material in the receptacle 1.

The gears 23, 24 and 25 are provided with a housing which is water proof so that the gears will be protected from moisture. This water proof housing is clearly shown in Figs. 1 and 2, the bottom being formed by a part of the member 22 and the top by the plate 22a, which engages the upstanding part 22b. The shafts 19 and 20 have their ends projecting into this housing through openings, which are provided with the leak proof stuffing boxes 22c. These stuffing-boxes also preferably contain and support the roller bearings 22d. The receptacle 1 is provided with a discharge opening 38 having a cover 39. The motor is preferably provided with a casing 40. A support 41 of any suitable material is provided for receiving containers into which the material from the receptacle 1 is discharged through the opening 38. This support is provided with an upstanding edge 42 which fits over a supporting piece 43, a portion of the support 41 resting on the member 44, which may be the top of the cabinet. The support is placed in position by tilting the outer end upwardly and placing the upstanding edge 42 under the supporting piece 43, and then lowering it to its supporting position. This support is removed in the same manner by tilting it upwardly and disconnecting the upstanding edge 42 from the holding piece 43. The position of the portion of the support

receiving the receptacle will depend, of course, upon the height of the receptacle, and will be in such position to permit the receptacle, when placed on it, to receive material from the opening 38.

Instead of having the metal or soldered contact between the coils and the receptacle 1, I may enclose the coil and put some liquid, such as brine, inside the enclosure, as shown in Fig. 9, this brine being cooled by the coil and having an intimate contact with the receptacle, thereby securing high efficiency.

I claim:

1. A device for freezing liquids comprising a receptacle for the liquid, a discharge opening for said receptacle, a fixed part below said opening, an outwardly projecting supporting piece on said fixed part, a tray having an upstanding edge and adapted to be tilted to place the upstanding edge under said supporting piece so that the tray will be held in horizontal position below said discharge opening.
- 15 2. A device for making ice cream comprising a base, a freezing receptacle mounted upon and supported by said base with its axis disposed vertically, said freezing receptacle including an interior metal container with a cooling element thereabout, a stirring device in said receptacle, a vertical shaft connected therewith and projecting from the receptacle, a motor in vertical alignment with said receptacle, a driving connection between said motor and said shaft, and means separate from the motor for controlling the movement of said stirring device.
- 25 3. A device for making ice cream comprising a base, a freezing receptacle mounted upon and supported by said base with its axis disposed vertically, said freezing receptacle including an interior metal container with a cooling element thereabout, a stirring device in said receptacle, a vertical shaft connected therewith and projecting from the receptacle, a motor in vertical alignment with said receptacle, a driving connection between said motor and said shaft, said stirring device comprising a bottom member with which said shaft is connected, two stirring shafts mounted on said bottom member, having beater arms, and means controlled from the exterior of the device and separate from the motor, for causing said stirring shafts to cease to rotate about their axes while moving around said base.
- 30 4. A device for freezing liquids comprising a base, a freezing receptacle mounted upon and supported by said base with its axis disposed vertically, said freezing receptacle including an interior metal container with a cooling element thereabout, a stirring device in said receptacle, a vertical shaft connected therewith and projecting from the receptacle, a motor in vertical alignment with said receptacle, a driving connection between said motor and said shaft, said stirring device comprising a bottom member with which said shaft is connected, two stirring shafts mounted on said bottom member, having beater arms, and means controlled from the exterior of the device and separate from the motor, for causing said stirring shafts to cease to rotate about their axes while moving around said base.
- 35 5. A device for making ice cream comprising a base, a freezing receptacle mounted upon and supported by said base with its axis disposed vertically, said freezing receptacle including an interior metal container with a cooling element thereabout, a stirring device in said receptacle, a vertical shaft connected therewith and projecting from the receptacle, a motor in vertical alignment with said receptacle, a driving connection between said motor and said shaft, said stirring device comprising a bottom member with which said shaft is connected, two stirring shafts mounted on said bottom member, having beater arms, and means controlled from the exterior of the device and separate from the motor, for causing said stirring shafts to cease to rotate about their axes while moving around said base.
- 40 6. A device for freezing liquids comprising a base, a freezing receptacle mounted upon and supported by said base with its axis disposed vertically, said freezing receptacle including an interior metal container with a cooling element thereabout, a stirring device in said receptacle, a vertical shaft connected therewith and projecting from the receptacle, a motor in vertical alignment with said receptacle, a driving connection between said motor and said shaft, said stirring device comprising a bottom member with which said shaft is connected, two stirring shafts mounted on said bottom member, having beater arms, and means controlled from the exterior of the device and separate from the motor, for causing said stirring shafts to cease to rotate about their axes while moving around said base.
- 45 7. A device for making ice cream comprising a base, a freezing receptacle mounted upon and supported by said base with its axis disposed vertically, said freezing receptacle including an interior metal container with a cooling element thereabout, a stirring device in said receptacle, a vertical shaft connected therewith and projecting from the receptacle, a motor in vertical alignment with said receptacle, a driving connection between said motor and said shaft, said stirring device comprising a bottom member with which said shaft is connected, two stirring shafts mounted on said bottom member, having beater arms, and means controlled from the exterior of the device and separate from the motor, for causing said stirring shafts to cease to rotate about their axes while moving around said base.
- 50 8. A device for freezing liquids comprising a base, a freezing receptacle mounted upon and supported by said base with its axis disposed vertically, said freezing receptacle including an interior metal container with a cooling element thereabout, a stirring device in said receptacle, a vertical shaft connected therewith and projecting from the receptacle, a motor in vertical alignment with said receptacle, a driving connection between said motor and said shaft, said stirring device comprising a bottom member with which said shaft is connected, two stirring shafts mounted on said bottom member, having beater arms, and means controlled from the exterior of the device and separate from the motor, for causing said stirring shafts to cease to rotate about their axes while moving around said base.

JAMES S. KNIGHT.
